VANITY BOX

Frederick John Cuthbertson, Greenwich, Conn.
Application October 28, 1954, Serial No. 32,853

Term of patent 14 years
(Cl. D86—10)

Fig. 1-

Fig. 2-

Fig. 3-

Fig. 1 is a top plan view of a vanity box embodying my new design;

Fig. 2 is an end elevational view thereof; and

Fig. 3 is a top perspective view thereof.

I claim:

The ornamental design for a vanity box, substantially as shown.
